UNITED STATES PATENT OFFICE.

VALSY E. ROWLAND, OF INDIANAPOLIS, INDIANA.

SKYLIGHT.

1,331,825.

Specification of Letters Patent. Patented Feb. 24, 1920.

Application filed October 31, 1919. Serial No. 334,812.

To all whom it may concern:

Be it known that I, VALSY E. ROWLAND, a citizen of the United States, residing at Indianapolis, in the county of Marion and State of Indiana, have invented certain new and useful Improvements in Skylights, of which the following is a specification.

This invention relates to skylights for ventilating and furnishing light to rooms next to the roofs of buildings, and the object of the invention is to provide a skylight which is thoroughly weather-proof, and also to provide novel and improved operating means whereby the skylight can be easily opened or closed.

The invention also has for its object to provide a skylight which automatically closes in case of fire.

A further object of the invention is to provide a novel and improved means for supporting the glass panes of the skylight.

Other objects and advantages of the invention will be pointed out in the detailed description appearing hereinafter, and in order that the invention may be better understood, reference is had to the accompanying drawings, forming a part of this specification.

30 In the drawings:

Figure 1 is an elevation showing one side of the structure; Fig. 2 is a cross-section on the line 2—2 of Fig. 1; Figs. 3, 4 and 5 are enlarged sectional views on the lines 3—3, 4—4, and 5—5, respectively, of Fig. 1; Fig. 6 is an enlarged cross-section of the structure at the ridge thereof, showing a flashing, one of the skylight sections being shown in open position; Fig. 7 is a cross-section on the line 7—7 of Fig. 2, and Fig. 8 is a sectional detail of a latch device.

Referring specifically to the drawings, 10 denotes a roof having a light-well, the curb of which latter is composed of side and end walls 11 and 12, respectively, said walls being arranged to support a skylight of the gable-roof type. The skylight is composed of two sections, which are pivotably connected at their upper ends to the opposite sides of a ridge beam 13 supported by the end walls 12 of the curb.

The frame of each skylight section is composed of top and bottom bars 14 and 15, respectively, stiles 16, and muntin bars 17. The frame is somewhat longer than the curb so as to project from the ends

thereof. The projecting ends of the frame are fitted with sheet metal panels 18, whereas the remainder of the frame, which is above the light-well, is glazed, the panes 60 being shown at 19.

It will be noted that the stiles 16 are considerably longer than the skylight and at their upper ends they project from the corresponding end of the skylight to serve 65 as a counterbalance. The stiles are I-beams and to their projecting ends, at the sides thereof, are attached weights 20. These weights may be attached to the projecting ends of the stiles at any distance from the 70 pivot of the skylight to obtain the proper counterbalancing effect. Where the stiles of the two skylights cross, the ridge beam 13, which is an I-beam, is recessed as shown at 21, to enable the stiles to clear the same. 75

The hinges for the skylight sections consist of leaves 22 and 23, connected by pins passing through knuckles thereon, the leaves 22 being secured to the sides of the ridge beam 13, and the leaves 23 to the 80 upper side of the top bars 14 of the skylight frames.

Means are provided for swinging the skylight sections open or closed, and as the operating means for the two sections are 85 the same, a description of one suffices for both.

To the under side of one of the muntin bars 17 is fastened an arm or beam 24, braced by a bar 25 extending diagonally 90 between the same and the muntin bar. The arm 24 is perpendicular to the skylight section, and it extends inward and downward. To the free end of the arm 24 is fastened one end of a hauling line 26, which extends over 95 to the curb side wall 11, on which the skylight section seats at its lower end, and on said wall is mounted a guide pulley 27, over which the line passes and then extends downward in the light-well, to any convenient location from which it may be operated. It will therefore be seen that a pull on the line 26 causes the skylight section to swing outwardly to open position and when the line is released said section swings down and 100 closes. In the depending portion of the line 26 is interposed a fusible link 28. In case of fire, this link melts so that the line is released, and the skylight section then automatically swings closed. It will be understood that the counterbalance hereinbefore described will be so arranged that the 105

110

skylight sections have a normal tendency to swing closed when released, and at the same time but little effort is required to swing them outward to open position.

5 The guide pulley 27 is carried by a latch lever 29, pivoted as shown at 30, in a recess 31 in the top of the wall 12, and having a hook-shaped end adapted to engage a keeper strip 32 on the bottom bar 15 of the sky- 70

10 light frame. A spring 33 presses against the latch lever and holds the same in locking position. The skylight section is therefore securely latched when it is closed. A pull 15 on the line 26 to open the skylight section, first swings the latch bar out of engagement with the keeper 32, and a continued pull on the line opens the skylight section. 75

At 34 is shown a chain fastened at one end to the muntin bar 17 adjacent to the curb end 20 wall 12, and on said wall is a guide pulley 35 over which the chain passes and then extends downwardly into the light well,—its lower end carrying a small weight 36. When the skylight section is swung open, the 25 weight 36 upon reaching the pulley 35, acts as a stop to limit the outward swing of the skylight section. It will be understood that a stop device will be provided for each skylight section, and at each end. 80

30 The bottom cross-bar 15, of the skylight frame is an angle or L-bar, placed so that its angle faces inwardly. This bar seats on the curb sidewall 11 when the skylight section is closed, said wall being shaped at the top, 35 as shown at 37, to enter the angle of the bar, whereby a tight, weatherproof joint is obtained. 85

To the top flanges of the ridge beam 13 are secured metal flashing strips 38, which 40 overlap the upper ends of the skylight frames, to obtain a weatherproof joint at these points. The strips are flexible so that they may readily bend when the skylight sections are swung open or closed. 90

45 To the top of each sidewall 11 of the curb wall, is secured a sheet metal gutter 39, extending throughout the entire length of the curb and spilling on the roof of the building, outside the end walls 12, of the 50 curb. This gutter catches any moisture from leaks or condensation running down the skylight sections on the inside thereof. 95

The muntin bars 17 of the skylight frames are of inverted T-shaped cross section, the 55 flanges being at the bottom to provide seats for the side edges of the glass panes 19. Extending parallel to the muntin bars are gutters 40, made out of a single piece of sheet metal which seats against the bottom of the 60 bar, as shown at 41, and has folds over the edges of the flanges thereof, and on top of the latter as shown at 42, the gutters being at the edges of the flanges. The pane seats on the part 42 whereby it is spaced from the 65 top of the flanges of the muntin bar, the 100

space thus formed being filled with putty as shown at 42a. Over the upstanding portion of the muntin bar is placed a cap 43, of sheet metal, held by a wire 44, and having outstanding bends 45 or flanges at the bottom, positioned above the pane 19, in spaced relation therewith, so that the pane may be puttied as shown in Fig. 4. The outer ends of the bends 45 are bent down into contact with the top surface of the pane. 105

On top of the top cross bar 14 of the skylight frame is fastened by a bolt 47, a sheet metal strip 48, having an upward triangular bend 49, which forms a ridge on which the upper end of the glass pane 19 seats, and the strip is then continued upward as shown at 50, to seat against the upper edge of the muntin bar 17, coming flush with the top thereof. This leaves a pocket for putty, as shown at 50a, and when the flashing 38 comes 110 down over it, a weatherproof joint is had. 115

The lower end of the pane 19 seats on a ridge 51 made in a sheet metal strip 52 secured to the cross bar 15 by a screw 53, which latter also forms a stop for the lower 120 edge of the pane. 125

It will, of course, be understood that all the panes 19 are secured in the skylight frames in the manner hereinbefore described. 130

The skylight sections are so dimensioned that when they are open, they overhang the curb walls 11 and 12, sufficiently so that they need not be closed during ordinary storms. 135

The preferred embodiment of the invention has been disclosed, but it will be understood that various changes and modifications may be made without a departure from the spirit and scope of the invention as claimed hereinafter. The invention is also 140 applicable to green-houses, wooden skylights, and doors above roofs, whether of wood or iron, and single or double. 145

I claim:

1. The combination with a hinged skylight and a curb on which the same seats; of a means for swinging the skylight to open position, said means comprising a hauling line, means for connecting the line to the skylight, a pulley over which the line passes, a pivoted support on the curb for the pulley, and a latch on said support engageable with the skylight when the same is closed. 110

2. The combination with a hinged skylight and a curb on which the same seats; of a means for swinging the skylight to open position, said means comprising a hauling line, means for connecting the line to the skylight, a pivoted latch on the curb engageable with the skylight when the same is closed, and a pulley carried by the latch, over which pulley the aforesaid line passes. 115

3. The combination with a hinged skylight and a curb on which the same seats; of a means for swinging the skylight to open po- 120

sition, said means comprising a hauling line, means for connecting the line to the skylight, a pivoted latch on the curb engageable with the skylight when the same is closed, and an operative connection between the latch and the aforesaid line.

4. The combination of a ridge beam, skylights hinged to the ridge beam, and flexible flashing strips carried by the ridge beams and seating loosely on the skylights across the joints between the same and the ridge beam.

5. The combination with a hinged skylight; of counterbalances at the ends thereof, and consisting of projecting beams, said beams and the skylight being located respectively on opposite sides of the hinge connection of the latter.

6. The combination with a hinged skylight; of counterbalances at the ends thereof, and consisting of projecting beams, said beams and the skylight being located respectively on opposite sides of the hinge connection of the latter, and weights carried by the projecting beams.

7. A skylight structure comprising a

frame composed of top and bottom cross bars, stiles and muntin bars, glass panes supported by the cross bars and the muntin bars, strips mounted on the cross bars and 30 having ridges on which the panes seat, the strips of the top cross bar having upstanding portions extending between the muntin bars, and stops on the bottom cross bar for the bottom edges of the panes.

8. A skylight structure comprising a frame composed of top and bottom cross bars, stiles and muntin bars, glass panes supported by the cross bars and the muntin bars, strips mounted on the cross bars and 40 having ridges on which the panes seat, the strips of the top cross bar having upstanding portions extending between the muntin bars, and stops on the bottom cross bar for the bottom edges of the panes, the aforesaid muntin bars having outstanding base 45 flanges for supporting the panes, and cap pieces on the muntin bars having outstanding base flanges engageable with the top of the panes.

In testimony whereof I affix my signature.
VALSY E. ROWLAND.
